6 Claims. (Cl. 292—49)

1

This invention relates to improvements in locks. It is an object of the invention to provide a simple form of lock including spring urged jaws on opposite sides of the latch which are normally held by the latter at an inclination to one another and contiguous to correspondingly inclined faces on a striker plate.

Another object of the invention is to provide such a lock wherein a projection is formed on the striker plate which moves the latch as the door is being shut, and this latch movement permits the spring urged jaws to turn so that upon opening movement of the door they move freely from between the inclined faces of the striker plate.

A further object of the invention is to provide a lock including a latch for engagement with a striker plate and a bolt mounted in the lock for movement parallel with the latch and having forwardly extending arcuate members adapted to travel along oppositely curved paths through slots formed in the striker plate so that even if the hinges are removed from the door it is virtually impossible to move the hinged side of the latter sufficiently from the door frame to obtain ingress or egress.

Having thus briefly stated some of the objects and advantages of the invention I will now describe it in detail with the aid of the accompanying drawings, in which:

Figure 1 is a side elevation of the lock with the cover largely broken away and showing parts in sections.

Figure 2 is a front view of the lock ignoring the striker plate.

Figure 3 is a partial side view showing the latch retracted, and

Figure 4 is a front view of Figure 3.

Figures 5 and 6 are sections on the line 5—5 and 6—6 respectively of Figure 1.

Figure 7 is a view on the line 7—7 of Figure 1.

Figures 8, 9 and 10 are sections on the lines 8—8, 9—9 and 10—10 respectively of Figure 1.

Referring to the drawings, 1 designates a casing having a removable cover 2 secured on one side thereof by screws 3. A removable plate 4, the ends of which project beyond the ends of the casing for attachment to a door (not shown), forms on edge face of the said casing and has lugs 4a thereon through which screws 5 extend in threaded engagement therewith, the said screws also passing through one casing side. Formed integral with the removable plate 4 intermediately of its height and projecting forwardly from one vertical edge of the latter is an

2

element 6 one face 7 of which is disposed at right angles to the outer face of the said plate. The element 6 is slotted at 8 centrally of its height through its face 7.

Mounted for reciprocating movement in the casing is a slide 9 having a latch 10 on one extremity which normally projects through an opening 11 in the plate 4. This opening is so positioned that the horizontal center line therethrough is in alignment with the horizontal center line through the slot 8. Provided in the casing is a guide 12 through which the slide 9 extends, and between the guide and the latch 10 a helical spring 13 is provided around the slide to urge the latch outwardly through the opening 11. On the extremity of the slide 9 remote from the latch 10 is a contact plate 14 for engagement by an arm 15 extending from an annular rotary plug 16. Any conventional means may be employed for turning the plug and imparting movement to the arm 15 to retract the slide 9 and draw the latch 10 inwardly; for the sake of simplicity the plug 16 is shown provided merely with a multi-sided axial aperture and its apertured ends are rotatably mounted in openings formed through the cover 2 and through the opposite side of the casing 1.

Pivoted on a screw 18a in engagement with the plate 4 on each side of the latch 10 is a jaw 18. Each jaw has a slot 19 formed in its face which rests against the plate 4 and projecting outwardly from the latter and extending into the slot 19 is a pin 20. Mounted in the slot 19 with one extremity bearing against one end of the latter and its opposite extremity against one side of the pin 20 is a helical spring 21 which tends to turn the jaw about its axis 18a toward the latch 10. The opposite side of the latch contacted by the opposed inner faces of the jaws 18 are so shaped that as the latch moves outwardly through the opening 11 the jaws are turned outwardly about their axes against the tension of the springs 21, then the outer sides 18b of the jaws, which are flat, are outwardly inclined from their pivoted extremities to lie contiguous to and parallel with opposite inclined walls 22a of a recess 22 in a striker plate 23 which is adapted to be mounted on a door frame (not shown). 18c denotes opposed inwardly projecting fingers on the jaws 18 to limit positively the outward rotary movement of the jaws.

Formed integral with the base of the recess 22 is an extension 24 which is positioned opposite the element 6 when the door (not shown) on which the casing is mounted is shut. At that

time the extension covers the slot 8 and a keeper 25 formed on the base of the recess and extending over the extension 24 projects into the slot 8. In order that the latch 10 may move freely over the keeper 25 as the said latch travels outwardly through the opening 11 the latter has its keeper contacting extremity rounded as shown at 10a. Formed integral with the inner opposed faces of the jaws 18 and of lesser height than the latter are inwardly projecting guides 26 the undersides of which ride upon the plate 4. The inner opposed faces of the guides are substantially parallel when the latch 10 is outwardly projected, and as the latch is retracted, due to the form of the opposite latch sides and the action of the spring 21, above described, these guides are turned so that they are inclined toward one another from their pivoted ends, and then, of course, the inner opposed faces of the jaws above the guides are parallel. Then these inner upper faces of the guides 26 form ways upon which the keeper 25 slides between the inner parallel sides of the jaws. As soon as the keeper 25 has passed over the adjacent end of the latch 10, during the locking operation, the latch is returned to its normal outwardly projecting position by the spring 13 and by this movement of the latch the jaws are moved to their outwardly inclined positions so that their outer faces 18b move into engagement with the inclined walls 22a of the recess 22 in the striker plate 23, so that the lock is held positively in engagement with the striker plate until the latch 10 is again withdrawn in to the casing and the jaws 18 are turned inwardly by the springs 21 to their striker plate releasing positions.

Mounted also for movement in the casing 1 parallel with the slide 9 is a member 30 which in the present instance is slotted intermediate of its length to receive a guide element 31 integral with one side of the said casing. Formed also in one longitudinal margin of the member 30, which is held against accidental movement by a spring 39, is a recess 32 into which an arm 33 extending from a rotary plug 34 projects. Any means may be provided for turning the plug; in the present instance, for the sake of simplicity, an axial multi-sided opening is formed through the plug and one apertured end thereof is rotatably mounted in an opening formed through the cover 2 and its opposite apertured end is rotatably mounted in the opposite side of the casing 1. Pivoted on the member 30 are two arcuate bolts 35 which are forwardly and outwardly curved from one another, and formed through the plate 4 are longitudinally spaced openings 36 through each of which one of the bolts 35 extends. Through the striker plate 23 opposite the plate openings 36 other openings 37 are provided. When the member 30 is moved toward the plate 4, by rotation of the plug 34 and movement of the arm 33, the bolts 35 are outwardly projected through the openings 37 along a curved path to render their detachment from the striker plate extremely difficult. By spacing the bolts 35 some distance above and beneath the latch 10, and also due to the fact that the openings 37 are well spaced from one another the locking means (that is the bolts 35 and the latch 10) render it practically impossible, even after removal of the hinges, to move a door sufficiently far from its frame to permit access for anyone however small.

While in the foregoing the preferred embodiment of the invention has been described and

shown it is understood that alterations and modifications may be made thereto to provide the said alterations and modifications fall within the scope of the appended claims.

5. What I claim is:

1. A lock including a casing having an opening through one side, a latch mounted for movement through said opening to retracted or outwardly projected position, jaws pivoted on the outer face of the casing on opposite sides of the latch, and means for turning the jaws when the latch is moved whereby when the latch is retracted the outer faces of the jaws are parallel and when the latch is outwardly projected the said outer faces are inclined to one another, in combination with a striker plate having opposed inclined walls thereon between which the jaws are adapted to be inserted, the inclination of the walls corresponding to that of the outer sides 15 of the jaws when inclined to one another whereby said jaws are engaged by said walls when the lock is closed.

2. The combination in claim 1, including a keeper on the striker plate positioned to engage 25 and retract the latch thereby turning the jaws so that their outer sides are parallel for entry between said walls as the lock is being closed.

3. The combination in claim 1, including a keeper on the striker plate positioned and shaped 30 to obstruct passage of the latch when the latter is outwardly projected and the lock is shut.

4. The combination in claim 1, including a keeper on the striker plate to engage and retract the latch as the lock is being closed to turn the jaws for entry between the walls, and guides on the inner opposed sides of the jaws for passage of the keeper thereover prior to its engagement with the latch as the lock is being closed.

5. A lock including a casing having an opening 40 formed through one side, a latch mounted for movement through said opening, means urging the latch outwardly, means for retracting the latch, jaws pivoted on the outer face of the casing on opposite sides of the latch, means retaining each jaw in contact with one side of the latch, the latter having its opposite sides so shaped that upon movement of the latch the jaws are turned about their axes so that when the latch is retracted the outer faces of the 45 jaws are substantially parallel and when the latch is outwardly projected the outer faces of the jaws are inclined to one another, in combination with a striker plate having a recess formed across it, the opposite walls of the recess being inclined to correspond to the inclination of the jaws when the latch is outwardly projected whereby when the latch is outwardly projected said jaws are adapted to be engaged by said walls.

6. A lock including a casing having an opening 55 through one side, a latch movable through the opening to retracted or outwardly projected positions, means for moving the latch, jaws pivoted on the outer face of the casing and bearing against opposite sides of the latch, spring means urging each jaw against one side of the latch, the latter being so shaped that outward movement thereof turns the jaws outwardly so that their outer faces are inclined to one another, in combination with a striker plate having a recess therein opposite walls of which are inclined for engagement by the outer sides of the jaws when the latter are inclined to one another, and means on the striker plate for re-

tracting the latch prior to the entry of the jaws into the recess as the lock is being closed.
